UNITED STATES PATENT OFFICE.

GUSTAV SEGSCHNEIDER, OF YONKERS, NEW YORK.

MACHINE FOR IRONING DOWN CURLS OF HAT-BRIMS.

SPECIFICATION forming part of Letters Patent No. 624,691, dated May 9, 1899.

Application filed January 11, 1899. Serial No. 701,789. (No model.)

To all whom it may concern:

Be it known that I, GUSTAV SEGSCHNEIDER, a citizen of the United States, residing in Yonkers, in the county of Westchester and State of New York, have invented certain new and useful Improvements in Machines for Ironing Down the Curls of Hat-Brim, of which the following is a specification.

In the manufacture of hats heretofore the hat after being curled was subjected to a so-called "flanging operation," by which the proper shape was imparted to the curl. This was accomplished by the action of a flanging-iron which acted on the curl of the brim while the hat was placed on a flanging-block. The iron was operated by hand, the hat being covered by a cloth during the flanging operation. The hat was then braided at the edge of the curl and again flanged and ironed, so as to give the final shape to the curled brim.

The object of this invention is to dispense with the first flanging operation, which was done by the use of a hand-operated iron and which was fatiguing work, especially in the summer season, and produce in place of this flanging operation the ironing down of the curl of the brim by means of a heated ironing-tool in connection with a suitable templet placed on the brim, so that afterward only the so-called "rounding," "edge-braiding," and second flanging or finishing of the hat are required. This would save the fatiguing first flanging operation and use in place of the same an ironing-down machine for the curls of the brim, by which this operation is accomplished in a quicker and more economical manner than heretofore.

My invention consists of certain features of construction and combinations of parts to be hereinafter described and then claimed.

In the accompanying drawings, Figure 1 represents a front elevation of my improved machine for ironing down the curls of hat-brims. Fig. 2 is a horizontal section on line 2 2, Fig. 1. Fig. 3 is a vertical transverse section, drawn on a larger scale, on line 3 3, Fig. 2. Fig. 4 is a horizontal section similar to Fig. 2, but showing in place of the flat folding-iron a rotary folding-iron. Figs. 5 and 6 are vertical transverse sections, respectively, of a smooth and fluted rotary folding-iron; and Figs. 7 and 8 are respectively a side elevation and a plan view of the folder for turn-

ing down the curl before it passes to the folding-iron.

55

Similar letters of reference indicate corresponding parts.

Referring to the drawings, A represents the supporting-frame of my improved machine for ironing down the curls of hat-brims. The frame A supports a stationary table A', on which is guided a vertically-movable table A², which is raised by means of cams a a, having toothed hubs a', that are engaged by horizontally-reciprocating racks a². On the movable table A² is supported a table B, which is covered with a layer of rubber, felt, or other elastic material, and to which rotary motion is imparted by intermediate bevel gear-wheels from a driving-shaft S at the rear of the machine. The rotary table B is raised and lowered with the movable table A² by means of a suitable treadle, which is not shown in the drawings. On the rotary table B is placed a hat-support C, which presses the hat down on the table, the brim of the hat extending around said support and being held in position by means of a metallic templet T, which is placed over the brim and below the curl of the same, said templet corresponding to the size and shape of the hat-brim, the curl of which is to be ironed down. The hat-support C consists of a bottom plate C', of wood or metal, and a retaining-ring C², which extends around the body of the hat and which bears on the top part of the brim, as shown in Fig. 3. The retaining-ring C² is preferably made of wood and provided with a circumferential sheet-metal band or loop C³, which protects the retaining-ring C² against the heat of the folding-iron, while it at the same time reduces the friction of the folding-iron with the retaining-ring C². The retaining-ring C² is further provided with a flange C⁴, which is provided at diametrically opposite points with 95 socket-holes d, that are engaged by pins d' of a yoke-shaped keeper D, the shank of which turns in suitable bearings of the top part of the supporting-frame A, said keeper receiving, preferably, positive motion simultaneously 100 with the hat-support by a bevel gear-wheel transmission from the driving-shaft S, as shown in Fig. 2.

To the rear part of the movable table A² is pivoted a supporting-bar F, which extends 105 transversely across the table A² and which is

guided in a keeper f near the front part of the table. The transverse bar F is provided with uprights f' , which carry fulcrumed arms f^2 , that are perforated at their upper ends, 5 said perforations serving as bearings for the gudgeons i of a flat hollow folding-iron I , which is provided with the usual gas and air supply pipes, so as to be heated by an interior gas-jet in the usual manner. The perforated 10 upper ends of the arms f^2 serve for setting the iron I higher or lower relatively to the table B , according to the position of the movable table A^2 . To the lower end of one of the arms f^2 is applied a helical spring f^3 , the opposite 15 end of which is attached to a stationary eye f^4 on a laterally-extending arm F' of the bar F , said spring serving to press the iron I against the retaining-ring C^2 . To the front end of the bar F is further attached a cord g , that is 20 connected with the upper arm of a fulcrumed elbow-lever g' , to the lower arm of which is applied a counterbalancing-weight g^2 , which serves to move the iron-supporting bar F , with the iron I , toward the retaining-ring C^2 , so as 25 to press the iron against the retaining-ring C^2 , while the helical spring f^3 produces the swinging of the arms f^2 and of the folding-iron toward the retaining-ring C^2 and templet T , so as to exert a downward pressure of the iron 30 on the curl of the hat-brim.

In front of the heating-iron I is arranged a folder H , which is shown in detail in Figs. 7 and 8 and which serves for the purpose of folding down the curl of the brim before the 35 same passes to the heated folding-iron I . The folder H is applied to a spring-wire H' , which is attached at one end to the supporting-frame A , while it is connected at its opposite end with a helical spring H^2 , which presses the 40 folder against the curl of the brim and templet, so as to produce the folding over of the curl. The tension of the helical spring H^2 , by which the folder is pressed against the curl of the brim and templet, is adjusted at 45 its rear end by a thumb-screw H^3 , which carries an eye, to which the rear end of the spring is attached, so as to adjust the tension of the folder for different sizes of hats and different sizes and thicknesses of brims.

50 The heated iron used for folding down the curl of the brim is made of oblong cross-section with flat sides, as shown in Fig. 1, and guided along the covering-band of the retaining-ring C^2 . For heavier brims it is necessary to apply greater power in ironing down the curl of the brim, and in these cases a rotary heating-iron is used, as shown in Fig. 4. This rotary heating-iron is made cylindrical and provided either with a smooth or with a 55 fluted surface, as shown, respectively, in Figs. 5 and 6. It is rotated by a suitable belt and pulley transmission inwardly over the folded curl of the brim, so as to press it with considerable force over the edge of the templet.

60 65 By the machine described the folded curl of the brim of the hat can be ironed down in connection with the templet before the curl

is rounded and braided, whereby the first flanging of the hat-brim is obviated and the hand labor heretofore required for ironing down the curl of the brim is dispensed with and substituted by the more reliable and effective machine-work. As the ironing down of the curl is accomplished without a covering-cloth, the expense for the cloth and the time necessary for the first flanging of the curl of the hat-brim are saved. The curls of the hat-brims are thereby ironed down with greater accuracy and uniformity, while the fatiguing hand labor heretofore required for this purpose is done away with and the same substituted by an easily-operated ironing-down machine that can be operated without requiring skilled labor for this purpose.

Having thus described my invention, I claim as new and desire to secure by Letters Patent—

1. In a machine for ironing down the curls of hat-brims, the combination, with a rotary table, and means for rotating the same, of a 90 hat-support on the table, said support being composed of a base-plate, a retaining-ring provided with an upper exterior annular flange and a rotary keeper engaging said flange, and a spring-actuated folding-iron, 95 substantially as set forth.

2. In a machine for ironing down the curls of hat-brims, the combination, with a rotary table, and means for rotating the same, of a 100 hat-support on the table, the said support being composed of a base-plate, a retaining-ring provided with an upper exterior annular flange and with a sheet-metal band below said flange and a rotary keeper connected with the 105 said flange, and a spring-actuated folding-iron, substantially as set forth.

3. In a machine for ironing down the curls of hat-brims, the combination, with a rotary table, and means for rotating it, of a hat-support on the table, a templet placed on the brim 110 of the hat, an oscillating and spring-actuated rotating folding-iron, and means for rotating it in an inward direction over the curl so as to iron down the folded curl of the brim, substantially as set forth.

4. In a machine for ironing down the curls of hat-brims, the combination, with a rotary table, and means for rotating it, of a support for the hat on the table, a templet placed over the brim of the hat, a folder for folding the 120 curl of the brim, a spring-wire for supporting the folder, means for adjusting the tension of said spring-wire, and a spring-actuated folding-iron near the folder, for ironing down the folded curl of the brim, substantially as 125 set forth.

In testimony that I claim the foregoing as my invention I have signed my name in presence of two subscribing witnesses.

GUSTAV SEGSCHNEIDER.
